UNITED STATES PATENT OFFICE.

JOHN H. McGRAW, OF OSWEGO, NEW YORK.

TUBE-EXPANDER.

SPECIFICATION forming part of Letters Patent No. 292,027, dated January 15, 1884.

Application filed August 4, 1883. (No model.)

To all whom it may concern:

Be it known that I, JOHN H. McGRAW, of Oswego, in the county of Oswego, in the State of New York, have invented new and useful 5 Improvements in Tube-Expanders, of which the following, taken in connection with the accompanying drawings, is a full, clear, and exact description.

The invention consists in a novel construction and combination of the constituent parts of a flue-expander, organized with the view of rendering the same simple, compact, and durable in construction, and capable of operating on flues and hose-couplings of almost any diameter with the utmost efficiency and convenience.

The invention is fully illustrated in the annexed drawings, wherein Figure 1 is a side view of my improved flue-expander. Fig. 2 is an end view of the same, with the gibs or compensating-blocks removed from between the body-sections for the purpose of illustrating more fully the connection of the body-sections by the yielding clamp or expandible ring applied to the exterior of the body. Fig. 3 is a longitudinal section on line *xx*, Fig. 2. Fig. 4 is a transverse section on line *yy*, Fig. 3, with the gibs in place. Fig. 5 is a longitudinal section of the expander, illustrating its adaptation 30 for operating on hose-couplings; and Fig. 6 is a detached isometric view of one of the gibs or compensating-blocks employed between the roller-carrying body-sections for maintaining them equidistantly apart at their joints when 35 distended.

Similar letters of reference indicate corresponding parts.

S denotes the operating-spindle of the tool, tapered in the usual manner, to spread apart 40 the rollers which expand the flue. Hitherto these rollers were either journaled in radially-elongated bearings in a rigid non-distensible collar or body, or journaled to the exterior of an expandible body which rotated with the 45 spindle. Such arrangements of parts, however, are defective and objectionable in several respects. In some of them the radial adjustment of the rollers is too limited, and therefore it requires different tools for different 50 sized flues; in others the axial support of the rollers is necessarily so frail as to deprive the

tool of its requisite stability and durability, and all of said tools expand the flue more or less flaring and press the flue with undue force against the edges of the flue-hole in the flue-sheet, and where said edges are sharp they are liable to cut the flue and weaken the boiler. 55

To obviate the aforesaid defects, I employ, in connection with the tapering spindle S, conversely-tapered rollers *r*, of sufficient length 60 to extend through the collar or body A, which surrounds the spindle, and is divided longitudinally, preferably into two semi-cylindrical parts, each of which is provided on its inner surface with two longitudinal channels, in 65 which two of the rollers are embedded and fitted loosely enough to allow them to freely rotate therein. The large end of the rollers projects from the face of the collar the requisite distance to reach into the flue sufficiently to 70 operate on the same in the flue-hole of the flue-sheet and a short distance inside of the boiler. The small end of the rollers projects from the opposite end or back of the collar A, and is provided with a circumferential groove, *a*, 75 into which fits a semicircular excision in the edge of a plate, *b*, which is detachably secured to the end of the collar-section. The internal longitudinal channels of the collar are of a depth to embrace about three-fourths of the 80 circumference of the rollers, the latter being inserted endwise in said channel, and retained therein by the plate *b* engaging the groove *a* of the rollers. I do not, however, limit my invention to the before-described means of securing the rollers in the collar, as it is obvious that the same can be accomplished by other means—as, for instance, by a circumferential diminution of the rollers inside of the collar, forming shoulders on the face of the same, and 85 a thread and nut or thimble and pin on the small end of the rollers. The collar with its rollers are held around the spindle by a yielding clamp, *d*, in the form of an expandible ring or coiled spring-band surrounding the collar. 90

In operating the described flue-expander, the spindle S is first withdrawn to allow the collar A to contract sufficiently to allow the protruding ends of the rollers to be inserted into the flue, the face of the collar being brought to 95 bear on the end of the flue. Then the spindle is forced between the rollers, to spread them 100

apart and bring them to bear on the interior of the flue, the spring-band d being of sufficient length to allow the collar A to expand to most any required diameter, and thus adapt 5 the tool to operate on flues of most any ordinary size. After the tool has been set for operation as aforesaid, a wrench is applied to the spindle to turn the same. In the rotation of the spindle the frictional bearing thereof 10 on the entire length of the rollers imparts rotation to the latter and causes them to traverse around the interior of the flue, the outward pressure of the flue being increased by driving the spindle farther into the expandible 15 collar A , and this being continued until the flue is properly expanded.

It will be observed that the large end of the tapering rollers produces a slightly greater 20 expansion of the flue inside of the boiler than at the end of the flue. This, in conjunction 25 with the usual beat subsequently formed on the end of the flue, firmly secures the flue to the flue-sheet without danger of excessive pressure of the flue on the sharp edges of the flue-hole in the sheet. Furthermore, the operation 30 of the large end of the rollers inside of the flue serves to retain the tool in its operative position.

To remove the expander from the flue, the 35 spindle S is withdrawn. The collar or body A will then automatically contract and liberate the rollers from the flue.

In order to maintain the collar-sections equidistantly distributed around the spindle during 40 the rotation of the latter, I insert between the collar-sections gibs or compensating-blocks d' , which are of the same depth as the collar, and of the requisite width to fill the space between the distended sections, as illustrated in 45 Figs. 1 and 4 of the drawings. This prevents the collar-sections from shifting, so as to widen the space between them on one side of the spindle and correspondingly close the space at the opposite side, which tendency is due to the circumferential strain exerted on the collar-sections by the rotation of the spindle.

For fastening hose to their couplings, I employ rollers r' , fitted to the collar or body A in the same manner as the rollers r , before 50 described; but the protruding large end of the roller r' , I provide with a circumferential rabbet, e , extending from the collar A to the tube-rolling portion s of the roller. Said rabbet is of a length to receive in it the coupling f , and 55 is sufficiently deep to allow the roller-end s to bear on and expand the ring g , which binds the end of the hose in the gland h of the coupling, as illustrated in Fig. 5 of the drawings.

Having described my invention, what I claim as new, and desire to secure by Letters Pat- 60 ent, is—

1. A flue-expander comprising a tapering spindle, conversely tapered rollers, and an expandible collar or body holding the rollers around the spindle, as specified. 65

2. A flue-expander consisting of a tapering spindle, an expandible body surrounding the spindle, and rollers interposed between said spindle and body and projecting with their ends at the face of the body, substantially as 70 set forth.

3. A flue-expander consisting of a longitudinally-divided collar or body, rollers partly embedded in the inner surface of the collar-sections and projecting at the end thereof, a 75 yielding clamp applied to the collar, and a tapering spindle passing through the collar between the inclosed rollers, substantially as described and shown.

4. In combination with the tapering spindle, the longitudinally-divided collar provided internally with longitudinal channels, tapering rollers arranged in said channels and projecting at the end of the collar, and provided at one end with a circumferential groove, 80 plates removably secured to the end of the collar-sections and engaging the groove of the rollers, and a yielding clamp applied to the exterior of the collar, all as described and shown. 85

5. In combination with the tapering spindle and tube-expanding rollers, the roller-carrying body, divided longitudinally, a yielding clamp applied to the exterior of the body, and gibs or compensating-blocks inserted between 90 the body-sections, substantially as and for the purpose specified. 95

6. In combination with the tapering spindle and expandible body, the interposed rollers projecting at the end of said body, and provided between the same and the tube-rolling portion of the roller with a circumferential rabbet, substantially in the manner described and shown, for the purpose set forth. 100

In testimony whereof I have hereunto signed 105 my name and affixed my seal, in the presence of two attesting witnesses, at Syracuse, in the county of Onondaga, in the State of New York, this 26th day of July, 1883.

JOHN H. McGRAW. [L. S.]
